Inventor
Timothy Michael Collins
Harry S. Gaither by Dyerforth, Lee, Clinton & Wilcox
Attest.

UNITED STATES PATENT OFFICE.

TIMOTHY MICHAEL COLLINS, OF CHICAGO, ILLINOIS.

GRIP MECHANISM.

Application filed December 16, 1918. Serial No. 263,996.

To all whom it may concern:

Be it known that I, TIMOTHY MICHAEL COLLINS, a citizen of the United States, residing at Number 126 West Randolph Street, 5 Chicago, in the county of Cook and State of Illinois, have invented a new and useful Improvement in Grip Mechanism, of which the following is a specification.

My invention relates to improvements in grip mechanism for use, generally stated, either as a means to revolve a body, as in the case of a wrench for pipes, flanges, fittings and valves, or as a means to arrest rotation of a body, for example, in the case of 10 a brake for wheels or other rotatable members in general.

My object, generally stated, is to provide a novel and simple construction of grip mechanism which shall operate positively 20 and by which the maximum grip may be effected; and as to its use as a wrench be readily and quickly adjustable to pipes, fittings, etc., of different sizes, and readily disengage therefrom, when desired.

Referring to the accompanying drawings, Figure 1 is a view in side elevation, partly sectional, of a wrench embodying my improvements showing the wrench applied to a pipe. Figure 2 is a plan view of the 30 structure shown in Fig. 1. Figure 3 is a section taken at the irregular line 3—3 on Fig. 1 and viewed in the direction of the arrows. Figure 4 is a perspective view of an adjustable block for engaging the flexible member 35 of the wrench which is looped about the article to be operated. Figure 5 is a view like Fig. 1 of a modification of the wrench shown therein. Figure 6 is a section taken at the line 6—6 on Fig. 5 and viewed in the 40 direction of the arrows; and Figure 7, a section taken at the line 7—7 on Fig. 5 and viewed in the direction of the arrows. The wrench shown in Figs. 1, 2, 3 and 4 is formed of a bar 8 having a ring-shaped extremity 9

45 presenting a circular aperture 10, and a flexible member 11 shown in the form of a chain and connected at one end with the portion 9 of the bar, and at its opposite end adjustably connected with the bar 8 at a different 50 point. The member 11 is formed at one end with a relatively wide link 12 which straddles the portion 9 of the bar and carries a cross-pin 13 which extends through the aperture 10, this part of the structure forming 55 the connection of the member 11 with the

ring portion 9, which, as will be noted, is of a shiftable character, for the purpose hereinafter explained. The opposite end of the member 11 passes slidably through the link 12 and is connected with the bars, preferably adjustably, as by the means shown and comprising a wedge-shaped block 14 presenting an inclined face 15, adjustably mounted in an opening 16 in the bar 8 and presenting an inclined face 17 opposing the face 15 of the block 14. The end of the member 11 which is preferably serrated along one face, as indicated at 18, to produce a rigid grip on the body to be operated, as, for example, that represented at 19, extends upwardly into the space between the block 14 and the adjacent wall of the opening 16, as shown, and is clamped by the engagement of teeth 20 on the block 14 with the opposing teeth 18 on the member 11. A 60 spring-pressed pin 21, provided with a finger-piece 22 and sliding in an opening 23 in the bar 8, enters a socket 24 in the block 14 to hold the latter in clamping position, as shown in Fig. 1, the block 14 containing an 65 other socket 25 on its narrower end which permits the block to be held to the bar 8, but out of a position in which it interferes with the adjustment of the member 11 in the opening 16, if the pin 21 is withdrawn 70 from the socket 24 and the block 14 is so adjusted that this pin enters the socket 25. The block 14, by preference, contains grooves 75 26 in its opposite sides, which, with ribs 27, on opposed walls of the opening 16, form 80 guides for the block 14 in the adjustment of the latter.

In the use of the wrench the member 11 is looped about the object to be operated, with the bar 8 in the position shown in 85 Fig. 1, and the end of the member 11 where it clamps the block 14 is adjusted, together with this block, to draw the member 11 taut about the object 19, as shown in Fig. 1. The operator then swings the bar 8 90 upwardly and to the left in Fig. 1, with the result of causing the member 11 to become tightly gripped about the object 19 and by the pressure thus applied rotating the latter, it being understood that 95 the member 11 in this operation rolling upon the outer surface of the ring 9, the pin 13 sliding forwardly in the ring, and thus the diameter of the looped portion of the member 11 becomes correspondingly re- 100 105 110

duced. It will be noted that by providing the shiftable pin 13 in connection with the member 11 and the ring 9, this end of the member automatically adjusts itself to different sized objects to which the wrench is applied, the slack in the member 11, when the handle-bar 8 is raised, being taken up by this automatic adjustment of the parts, and, when the handle-bar 8 is reversely operated, the member 11 automatically returns to slack condition.

The construction illustrated in Figs. 5, 6 and 7 is the same as that of the preceding figures, except that the adjustment, instead of being provided between the member 11 and the handle-bar 8 at the point of connection therewith in the rear of the pin 13, is provided between the link carrying this pin and a portion of the flexible member 11. 20 In this arrangement, the connection of the flexible member 11 with the handle-bar 8 in the rear of the pin 13 is through the medium of the pin 28, which by preference is non-adjustable and the link carrying the pin 13 and represented at 29 is provided with a hook-link 30 adapted to hook over any one of the joints of the flexible member 11. It will be readily understood that the action of the wrench of Figures 5, 6 25 and 7 in operating on an object is the same as that shown in the preceding figures. In this arrangement the inner surface of the flexible member 11, where it engages the object 19, is shown unserrated, but it will be readily understood that if desired serrations may be provided thereon to enhance the gripping effect, and also that they may be omitted from the construction of Fig. 1, if desired.

40 While I have shown my improvements as embodied in a wrench structure, it will be readily understood that the same principle of operation may be employed in a brake, or in fact in any mechanical device to which my improvements may be applicable, or, in other words, I intend to cover my invention broadly as a mechanical movement. Furthermore, the invention may be provided in forms of structure other than those shown, it being my intention to claim my invention as fully and completely as the prior state of the art will permit.

What I claim as new and desire to secure by Letters Patent is:

1. Grip mechanism comprising a bar, and a flexible member in the form of a loop with its ends extending in intersecting relation and operatively engaging said bar at 60 different points, the part of said member at which the latter connects at one end with said bar being automatically bodily shiftable relative to said bar in the act of shifting said bar relative to the object to be gripped, after application of said flex-

ible member to said object, said bar having a portion at which it engages said flexible member between the points of connection of the latter with said bar and upon which it moves when said bar is operated. 70

2. Grip mechanism comprising a bar containing an apertured extremity, and a flexible member with its ends extending in intersecting relation, provided at one end with a section which extends loosely into said aperture and forms a shifting connection between said member and bar, and operatively connected at its opposite end with said bar, said apertured extremity engaging with said flexible member between the 75 ends of the latter and upon which it moves when said bar is operated.

3. Grip mechanism comprising a bar containing an apertured extremity, and a flexible member provided at one end with 80 a section which extends loosely into said aperture and in the operation of the bar in the gripping of an object by the flexible member automatically moving along the wall of said aperture and thereby forming a shifting connection between said member and bar, said flexible member being operatively connected at its opposite end with said bar in the rear of said shiftable connection, said apertured extremity 85 engaging with said flexible member between the ends of the latter and upon which it moves when said bar is operated.

4. Grip mechanism comprising a bar containing an apertured extremity, the outer surface of which is rounded, and a flexible member provided at one end with a section which extends loosely into said aperture and forms a shifting connection between said member and bar, and operatively connected 100 at its opposite end with said bar, said rounded surface engaging with said flexible member between the ends of the latter.

5. Grip mechanism comprising a bar containing an apertured extremity, a flexible 110 member provided at one end with a section which extends loosely into said aperture and forms a shifting connection between said member and bar, and operatively connected at its opposite end with said bar to be adjustable thereon for adjusting said member to objects of different diameters, said apertured extremity engaging with said flexible member between the ends of the latter and upon which it moves when said bar is operated. 115

6. Grip mechanism comprising a bar having its extremity rounded and containing an aperture, and a flexible member provided at one end with a section which extends 120 loosely into said aperture and shiftable along the wall thereof, and is operatively connected at its opposite end with said bar to be adjustable thereon for adapting said flexible member to objects of different diameter, said 125

rounded surface engaging with said flexible member between the ends of the latter.

7. Grip mechanism comprising a bar having a ring-shaped extremity, and a flexible member in the form of a loop with its ends extending in intersecting relation, one end of said flexible member carrying a cross piece which extends into the opening in said ring-shaped extremity and is movable along the wall thereof, the other end of said member being connected with said bar at a point in the rear of said ring.

8. Grip mechanism comprising a bar having a recessed extremity, the bottom of said recess being of substantially curved form, and a flexible member in the form of a loop with its ends extending in intersecting relation, said member having a part at which it engages said bar at said recessed portion, and another part engaging said bar at another point thereon, the part of said member at which it engages the recessed portion of said bar being automatically bodily shiftable relative to said bar in the act of shifting said bar relative to the object to be gripped, after application of said flexible member to said object, the outer surface of said recessed portion of said bar engaging said member between its points of connection with said bar and moving along said member when said bar is actuated.

9. Grip mechanism comprising a bar and having a ring-shaped extremity, a flexible member in the form of a loop with its ends extending in intersecting relation, one end of said flexible member carrying a cross-piece which extends into said aperture and is movable along the wall thereof, and means adjustably securing the other end of said flexible member to said bars at a point in the rear of said ring.

10. Grip mechanism comprising a bar and having a ring-shaped extremity, a flexible member in the form of a loop with its ends extending in intersecting relation, one end of said flexible member carrying a cross-piece which extends into said aperture and is movable along the wall thereof, and means adjustably securing the other end of said flexible member to said bar at a point in the rear of said ring, comprising a block adjustable in an opening in said bar and engaging said flexible member, and means for releasably holding said block in position.

11. Grip mechanism comprising a bar and a flexible member in the form of a loop, with its ends extending in intersecting relation and operatively engaging said bar at different points, the part of said member at which the latter connects at one end with said bar being in front of the point of intersection of the ends of said member and automatically bodily shiftable in the act of shifting said bar relative to the object to be

gripped after application of said flexible member to said object.

12. Grip mechanism comprising a bar and a flexible member in the form of a loop, with its ends extending in intersecting relation and operatively engaging said bar at different points, said bar in the operation of the device rolling against one end of said member lengthwise of, and between the ends of, the latter, the part of said member at which the latter connects at its other end with said bar being automatically bodily shiftable in the act of shifting said bar relative to the object to be gripped after application of said flexible member to said object.

13. Grip mechanism comprising a bar and a flexible member in the form of a loop, with its ends extending in intersecting relation and operatively engaging said bar at different points, with one of said points of engagement being pivotal and extending in front of the point at which the ends of said member intersect, a portion of said bar extending in front of said point of intersection opposing the outer surface of said member and in the operation of the device rolling against a portion of said member in front of said point of intersection, for the purpose set forth.

14. Grip mechanism comprising a bar, a flexible member in the form of a loop with its ends extending in intersecting relation, and a pin connected with said member, said member engaging at said pin and at the other end of said member, with said bar, the connection of said member with said bar at said pin being automatically bodily shiftable relative to said bar in the act of shifting the bar after the application of said flexible member to its position of use, said bar having a portion at which it engages said flexible member between the points of connection of the latter with said bar and upon which it moves when said bar is operated.

15. Grip mechanism comprising a bar, and a flexible member in the form of a loop with its ends extending in intersecting relation and operatively engaging said bar at different points, the connection of said member at one end with said bar being shiftable and arranged to automatically shift relative to said bar in the act of shifting the latter after application of said member to its position of use, said bar having a portion at which it engages said flexible member between the points of connection of the latter with said bar and upon which it moves when said bar is operated.

16. Grip mechanism comprising a bar and a flexible member in the form of a loop with its ends operatively engaging said bar at different points, the part of said member at which the latter connects at one end with said bar being automatically bodily shiftable relative to said bar in the act of shifting said

bar relative to the object to be gripped, after application of said flexible member to said object, said apertured extremity engaging with said flexible member between the ends 5 of the latter and upon which it moves when said bar is operated.

17. Grip mechanism comprising a bar containing an apertured extremity, and a flexible member provided at one end with a 10 section which extends loosely into said aperture and forms a shifting connection between said member and bar, and operatively connected at its opposite end with said bar, said apertured extremity engaging with said 15 flexible member between the ends of the

latter and upon which it moves when said bar is operated.

18. Grip mechanism comprising a bar and a flexible member in the form of a loop operatively engaging said bar at different 20 points, said bar in the operation of the device rolling against one end of said member lengthwise, and between the ends of, the latter, the part of said member at which the latter connects at its other end with said 25 bar being automatically shiftable in the act of shifting said bar relative to the object to be gripped after application of said flexible member to said object.

TIMOTHY MICHAEL COLLINS.
